JOHN WRIGHT, OF POLLOKSHIELDS, GLASGOW, SCOTLAND.

DIES FOR USE IN THE MANUFACTURE OF INLAID LINOLEUM.

1,100,463.

Specification of Letters Patent. Patented June 16, 1914.

Application filed December 19, 1910. Serial No. 598,004.

To all whom it may concern:

Be it known that I, JOHN WRIGHT, a subject of the King of Great Britain and Ireland, and a resident of Pollokshields, Glasgow, Scotland, have invented certain new and useful Improvements in Dies for Use in the Manufacture of Inlaid Linoleum, and of which the following is the specification.

The invention relates to male and female dies of the type used for extruding successively separate tiles from separate and successive sheets of differently colored linoleum material onto a backing sheet upon which they are afterward secured and aggregated by passage through presses or calenders.

The machine in which the dies are used may be of the type in which the web of backing material is made to travel by a step-by-step motion from underneath each pair of male and female dies to underneath the succeeding pair, the dies being both raised when the backing material is traveling. At each step each separate and successive sheet of differently colored linoleum is brought into position between the two dies. This may be done in various ways; for example, continuous webs of the differently colored linoleum may be made to travel between the dies with a step-by-step movement; or sheets of linoleum may be introduced by hand between the dies. Or where the fabric is being made by hand, both dies as well as the sheets of linoleum are changed until the part of the pattern for the length of backing on the platen is made up.

The invention has for its object by providing simple and effective means for supporting certain parts of the female die during the process to obviate the necessity for those heavy and expensive female dies hitherto necessary, and rendering it possible to use instead thin and light female dies easily and cheaply produced and easily handled.

It is obvious that as the process proceeds, certain parts of successive female dies become supported during the descent into them of the male dies by tiles already laid from other dies upon the backing material. Other parts are not so supported, and it is because of these unsupported parts that it has been necessary to make the female dies sufficiently heavy and substantial to resist the pressure put upon them at the descent of the male die. Where there is a tile lying upon the backing under a female die, that die

upon the descent of the male die rests upon the tile, and the tile being supported by the platen or table beneath the backing the weight is thrown thereupon and its strength 60 is adequate to resist the pressure applied.

According to the invention, there are provided at such parts of the various and successive female dies as there be no tiles beneath, means for transferring the load imposed by the descending male die from the female die to the platen beneath the backing. These means consist of ribs, pins, or plates of adequate resistance and of a thickness 65 equal to the material of the tiles applied beneath the female die.

In order that the invention and the manner of performing the same may be properly understood there is hereunto appended a sheet of explanatory drawings showing diagrammatically in Figure 1 a plan of a series of tiles of different colors to be deposited, similarly in section in Fig. 2 a female die, a male die, a backing sheet and a sheet of the linoleum material, similarly in Fig. 3 a 80 second female die and the other parts, and similarly in Fig. 4 a third female die and the other parts—it being understood that for the sake of clear illustration many details such as the platen upon which the backing material rests, the stripping plates for the dies and the other parts forming no part of the present invention are omitted. Figs. 5 to 8 inclusive are plan views of four successive dies for the manufacture of a piece 90 of inlaid linoleum in which four different colors are employed to form at intervals in a plain strip, a four color pattern.

In Fig. 1 there are indicated six color tiles A B C D E F to be successively deposited 95 upon a backing. Now, as in Fig. 2, let it be supposed that from the second color sheet B the first tile is to be extruded onto the backing sheet G (which lies upon the machine platen—not shown—) by a male die H 100 through a female die J. No former tile has been deposited, so the female die J is unsupported. There is therefore applied to its under side contiguously to the die aperture a series of supporting ribs J¹—which ribs 105 might instead be a series of short pins, or a plate covering the die, but in any case of a thickness equal to the thickness of the color sheet B.

In Fig. 3 the tile from the third color 110 sheet C is to be deposited, and accordingly the backing with the deposited tiles, B, is

freed from the dies, H and J, and the male dies, H², and female dies, J², for the tiles, C, come into use and are put in place over the deposited tile, B, with the result that the tile 5 B formerly deposited now supports part of the female die, therefore that die only requires support by the ribs J¹ or their equivalents at other parts contiguously to the die aperture. Again, in Fig. 4, the tile from the 10 fifth color sheet E is to be deposited. There are already two tiles B C in place to support the new female die J³, which is put in place over the already deposited tiles B and C. The ribs J¹ or their equivalents are arranged accordingly. And so on until for 15 the last color the last female die is supported by the previously deposited tiles of all the other colors and no ribs or equivalents are then required.

20 In Figs. 5 to 8 inclusive I have shown four successive dies used in the manufacture of a piece of inlaid linoleum in which four different colors are employed to form, at intervals in a plain strip, a four-color pattern.

25 Thus Fig. 5 shows the female die J through which pieces of linoleum are to be punched to deposit a number of squares all of one color on the backing beneath the female die. As there are no tiles of linoleum beneath this 30 first die, the apertures in the latter are surrounded by supports or ribs J¹ all around each aperture. Assuming that the dies are to be worked as in my Patent 1,005,587, all the pairs of male and female dies are raised, 35 and the backing then advanced a step. This brings the backing, with the tiles deposited thereon through the die in Fig. 5, beneath the female die in Fig. 6 in such position that the deposited tiles act as supports to the 40 second female die around parts of certain apertures in it, these deposited tiles being shown at B hatched in broken lines. The die, on the other sides of the apertures, not being supported by tiles underneath, requires to be supported there by the ribs. 45 The same thing takes place when the backing, with the tiles deposited on it by the dies in Figs. 5 and 6, has advanced beneath the die in Fig. 7. Here again where the die is 50 not supported by underlying tiles, ribs have to be used at the unsupported sides of the apertures. Finally, in Fig. 8, it will be seen that as tiles surround all the four sides of the apertures in it, no supporting ribs are 55 required around the apertures in the die

there used. If desired, this last die may be used to deposit the strips of plain linoleum between each longitudinal strip of pattern and the comparatively large apertures, in this case marked K, are surrounded by supporting ribs J¹. The strip of plain material, if deposited through this die, must, of course, be of the same color as the four pieces then being inserted in the pattern strips; but, if another color other than any of those already used is wanted for this plain part, another pair of dies would of course have to be provided, and the backing with the pattern strips on it advanced another step. Of course, when the fabric is 60 made by hand the dies as well as the sheets of linoleum may be changed and the backing on the platen not moved until the pattern is completed for that length of backing. 65

What I claim is:—

75 1. In a machine for making linoleum or the like, a female die of relatively light weight and overlying a suitably supported backing for tiles, said die having elements on its underside for spacing the bottom of the die above the backing and arranged so as to accommodate previously cut tiles carried by said backing, certain of said spacing elements being located immediately adjacent the die apertures and supported on the 80 backing, and said die having portions to receive thereunder and to rest upon previously cut tiles.

2. In a machine for making linoleum or the like, a series of female dies overlying a 85 suitably supported backing for tiles, said dies having die apertures and having bottom projections adapted to be supported from the backing and to space the dies above said backing, and to afford spaces to accommodate previously laid tiles, said projections being variously arranged only at the 90 edges of the die apertures which are unsupported by underlying tiles, and decreasing in 95 number in the dies arranged toward the discharge end of the machine, substantially as described.

100 In testimony whereof I have signed my name to this specification, in the presence of two subscribing witnesses.

JOHN WRIGHT.
